(57) **CLAIM**

The ornamental design for a limit switch, as shown and described.

DESCRIPTION

FIG. 1 is a top, front and right side perspective view of a limit switch showing a first embodiment of our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a left side view thereof, shown in an alternate position of use;
FIG. 10 is a top, front and right side perspective view of a limit switch showing a second embodiment of our new design;
FIG. 11 is a bottom, rear and left side perspective view thereof;
FIG. 12 is a front elevational view thereof;
FIG. 13 is a rear elevational view thereof;
FIG. 14 is a left side view thereof;

FIG. 15 is a right side view thereof;
FIG. 16 is a top plan view thereof;
FIG. 17 is a bottom plan view thereof; and,
FIG. 18 is a left side view thereof, shown in an alternate position of use.
The broken lines depict environmental subject matter only and form no part of the claimed design.
